UNITED STATES PATENT OFFICE.

RALPH A. D. PRESTON, OF AKRON, OHIO, ASSIGNOR TO THE GOODYEAR TIRE AND RUBBER COMPANY, OF AKRON, OHIO, A CORPORATION OF OHIO.

BALLAST DEVICE.

1,076,060.

Specification of Letters Patent.

Patented Oct. 21, 1913.

Application filed May 27, 1912. Serial No. 700,062.

To all whom it may concern:

Be it known that I, RALPH A. D. PRESTON, a citizen of the United States, residing at Akron, in the county of Summit and State 5 of Ohio, have invented new and useful Improvements in Ballast Devices, of which the following is a specification.

This invention relates to ballasting devices for use on instrumentalities employed in 10 aerial navigation.

The object of the invention, broadly speaking, is to convey to such an instrumentality, such, for instance, as a dirigible balloon, fluid ballast to replace the loss of 15 weight due to the use of fuel employed for propelling the balloon, or to counteract the increase in lifting power due to expansion of gas.

More specifically, the invention resides in 20 providing an instrumentality engaged in aerial navigation such, for instance, as a dirigible balloon, with means for pumping or otherwise conveying water from a body of water as a lake, river, sea, etc., over which 25 the balloon may at the time be passing to thereby replace the weight lost by the use of the fuel consumed in propelling the balloon, or to counteract the increase in lifting power due to expansion of gas.

With the foregoing and other objects in 30 view, the invention consists in the novel construction, combination and arrangement of parts constituting the invention to be hereinafter specifically described and illustrated 35 in the accompanying drawing which forms a part hereof wherein is shown the preferred embodiment of the invention, but it is to be understood that changes, variations, and modifications can be resorted to which come 40 within the scope of the claims hereunto appended.

Figure 1 is a diagrammatical view in side elevation of a dirigible balloon and so much 45 of the parts thereof as will serve to illustrate my invention in connection with which is shown my improved device for conveying water to the balloon for the purpose of ballasting the same. Fig. 2 is an enlarged view 50 partially in section and partially in side elevation of a form of pump employed for carrying my invention into effect.

Referring to the drawings in detail the reference numeral 1 denotes a dirigible balloon of any preferred type provided with 55 the usual car 2 suspended below and pro-

vided with one or more propellers 3 preferably, although not necessarily, revolved through the medium of internal combustion engines utilizing gas or gasoline as a fuel.

Experience has demonstrated that in cases 60 of spherical balloons or those which do not utilize a motor, one difficulty is to maintain the buoyancy of the balloon while on the contrary the constant use of a fluid and the loss of the weight thereby in operating or 65 navigating a dirigible balloon tends to increase the buoyancy of the balloon and consequent difficulty in keeping the balloon from assuming too high an altitude, and as the constant use of fuel is required for navigation purposes it becomes highly desirable 70 to replace the loss of the weight due to the fuel with some easily procurable substance and to supply this weight or ballast continuously in approximately as near a direct 75 ratio to the loss of weight due to the consumption of fuel as possible.

In order to accomplish the foregoing I 80 preferably secure to the balloon a pump 4 which is to be dragged in the water by means of tow-lines 5 suitably connected with various portions of the frame work and also connect the pump 4 with a storage tank or tanks 6 carried by the balloon through the medium of a flexible conductor, such as a 85 hose 7, so that as the pump 4 moves through the water the fluid in the pump 4 will be delivered to a receptacle carried by the balloon.

In the drawings, the pump 4 is illustrated 90 in detail only so far as is necessary to show a device having the functions of a pump, specific types of pumps which may be used being shown, described and claimed in the applications of Ralph H. Upson, filed July 95 22, 1912, Serial Nos. 710,953; 710,954; 710,955, and 710,956, but it is contemplated by this invention that the force or power derived or set up by the dragging or moving 100 of the pump body 4 through the water will generate sufficient energy to pump the water upwardly to the balloon.

It will be obvious when it is desired to take on ballast that all that is necessary to do is to lower the pump 4 into the water 105 and as the balloon moves forward a constant supply of fluid will be forced upwardly to the balloon sufficient to compensate for the loss of weight or ballast due to the consumption of fuel on board.

It will be obvious, of course, that various forms or types of pump may be used, or various types of conductors, and I therefore do not desire to limit myself to any specific type of pump in this application.

I claim:

1. The combination with an instrumentality designed for aerial navigation, of means adapted to depend therefrom and including an element having the functions of a pump, said element being adapted to raise fluid ballast to said instrumentality, said element being rendered active by movements of said instrumentality.
15. 2. The combination with an instrumentality designed for aerial navigation, of means adapted to depend therefrom and to raise fluid ballast to said instrumentality, said means being rendered active for this purpose by movements of the instrumentality.
25. 3. Means for ballasting an instrumentality designed for aerial navigation and including an element having the functions of a pump, said element being connected to said instrumentality and rendered active for this purpose by movements thereof through a fluid in the general direction of travel of the instrumentality.
30. 4. Means for ballasting an instrumentality designed for aerial navigation and

including an element having the functions of a pump, said element being connected to said instrumentality and rendered active for this purpose by movements thereof through a fluid in the general direction of travel of the instrumentality, the activity of the element providing a continuous supply to the instrumentality.

35. 5. The combination with an instrumentality designed for aerial navigation, of means functioning as a pump and rendered active when drawn through a fluid by movements of the instrumentality, for raising a portion of the fluid to said instrumentality to serve as a ballast therefor.

40. 6. The combination with an instrumentality designed for aerial navigation, of a pump-like means connected to and adapted to be drawn through a fluid by said instrumentality, tubular means connecting said instrumentality and said pump-like means for conveying fluid in a continuous stream from the latter to the former during the movement of the former above said fluid.

45. In testimony whereof I have hereunto set my hand in presence of two subscribing witnesses.

50. RALPH A. D. PRESTON.
